UNITED STATES PATENT OFFICE

DAVID F. DOUGAN, OF MEMPHIS, TENNESSEE

MATTRESS PICKER AND RENOVATOR

Application filed May 17, 1930. Serial No. 453,300.

This invention relates to machines for picking and renovating the cotton, hair or other filling of mattresses to thus renovate this filling and clean the same of dust and other foreign particles.

The general object of the invention is to provide a very simple mechanism of this character which will thoroughly pick apart the filling of the mattress, which will act by suction means to draw the dust and foreign particles therefrom, and which will discharge the cleaned and picked filling into a mattress tick.

A further object is to provide means whereby the filling may be blown into the tick and whereby the discharge of material into the tick may be stopped without stopping the operation of the machine.

A further object is to provide means whereby the material may be disinfected as it passes through the discharge chute into the mattress tick.

Other objects will appear in the course of the following description.

25 My invention is illustrated in the accompanying drawings, wherein:—

Figure 1 is a longitudinal sectional view through a picker and renovator constructed in accordance with my invention;

30 Figure 2 is a section on the line 2—2 of Figure 1;

Figure 3 is a section on the line 3—3 of Figure 1;

Figure 4 is a section on the line 4—4 of Figure 1;

35 Referring to these drawings, 10 designates a supporting frame of any suitable character and having the bearings 11 for a shaft 12. Disposed below this shaft and between the end frames 10 is the lower section 13 of a drum, the upper section of which is designated 14.

These sections are concentric to the shaft and the two sections are hinged to each other at 15 so that the upper section may be turned back to expose the interior of the drum. The shaft passes through the end walls of these drum sections. The inner faces of the drum sections are provided with longitudinally extending strips 16 carrying inwardly pro-

jecting teeth or pins 17. The upper section is provided with a relief port 18 having a door 19 held closed by buttons 20 under normal circumstances.

Mounted upon the shaft 12 and rotating within the drum are a series of pickers. The pickers are formed by a series of disks 21 having hubs 22 which are engaged to the shaft by means of set screws or any other suitable means. Disposed against each of these disks is a relatively thin metallic disk 23 having relatively long outwardly projecting webs or arms 24 provided at their ends with longitudinally extending relatively long teeth 25. Four of these teeth are illustrated, the outside teeth extending straight outward, the two middle teeth being reversely bent with relation to each other in opposite directions. As illustrated, there are four of these arms or webs 24 for each disk 23, but I do not wish to be limited to this number. The arms are shown as disposed in quartering relation to each other. Disks 23 are bolted to the disks 21 by means of the bolts 25a. At the entrance end of the machine, the shaft 12 is surrounded by a housing 26 in the form of a pulley mounted upon the shaft to prevent the filling such as cotton, hair or the like as it enters the drum from becoming wrapped around the shaft.

One end of the shaft is provided with the driving pulley 27 and also mounted upon this shaft inward of the pulley 27 is a power transmission pulley 28. At the opposite end of the frame, the lower section of the drum is formed with an opening 29.

Exterior to the lower section of the drum and discharging through this opening into the interior of the drum is the hopper 30. Disposed adjacent the inlet end of the drum is a section of screen material 31 of reticulated metal fabric which is supported upon the arcuate flanges 32 and mounted upon the inner face of the lower section of the drum.

The lower section of the drum adjacent the intake end thereof and beneath the screen 31 is provided with a dust box or trunk 33 which extends downward from the lower section of the drum and is formed with a bottom wall 100

which extends downward and laterally and opens into a dust door housing 34. In this housing, there is disposed the rotatable fan 35 which is mounted upon a shaft 36. This 5 shaft 36 is mounted in suitable bearings upon the end frames of the machine and carries upon it the pulley 37 driven from the pulley 28. The inlet opening of the dust box 33 is disposed immediately beneath the screen 31 so that the screen prevents the cotton, hair or other filling from being carried downward into the dust box. The exhaust fan 35 acts to withdraw all the dust and foreign matter which is liberated by the beating and 10 picking given to the material by the pickers 24. Remote from the inlet end of the drum is a horizontally extending discharge chute 38 whose lower wall at the rear end of the chute opens into a fan housing 39 in which 15 is disposed a rotatable blower fan 40. The rear end of the chute 38 is connected to the drum by the vertically extending trunk 41 which opens into the lower section of the drum and the opening of the trunk 41 into 20 the drum is controlled by a sliding door or valve 42 having a link connection to an operating rod 43 whereby the valve or door 42 may be closed or opened.

When the valve 42 is closed the discharge 25 of material from the drum is cut off and the fan will then act to discharge any material which may be in the chute into a mattress tick held with its mouth around the opening of the chute 38. Means are preferably provided whereby the open end of the tick may be held closely around the end of the discharge chute, but I do not wish to be limited to any particular means for this purpose.

It will be seen that with the construction 30 so far described, the filling of the mattress is fed in the hopper 30 and discharged into the drum. The picker blades 24 act to tear the material apart, loosen the packed fibres and thoroughly pick it. At the same time the 35 exhaust fan draws any dust or foreign matter out of the cotton, then discharges it into the dust box.

Preferably, there is provided a relief door 44 which may be used to reduce the air drawn 40 from the drum 13 so as to permit the amount of dust or dirt removed from the mattress filling to be regulated. Of course, by opening or closing the door 44 to a greater or less extent, it is possible to remove all of 45 the dirt or dust or remove part of it. The upper section of the drum is provided with an opening 45 normally closed by a door 46. When this door 46 is opened and with the fan 40 shut off, material will be forced out 50 on the floor instead of being discharged through the chute in case the machine should be used for cleaning cotton and other fibrous materials for use otherwise than for stuffing mattresses. This is for the reason that with 55 the regular discharge shut off, the material

which is fed into the drum through the hopper 30 must pass off somewhere and thus if the door 46 be opened, the material will be forced out. By opening the air relief door 19, suction exerted on the material by 70 the fan will be reduced.

Preferably, I provide means for spraying disinfectant on to the filling material as it passes through the chute 38 to the tick.

This is mounted upon the frame of the machine preferably beneath the dust box 33 and includes an air compressor 47, a tank 48 for holding the disinfectant and a sprayer 48^a discharging into the chute. The compressor or air pump will be operated from the lower shaft 36. I do not wish, however, to be limited to this as while this is a preferable construction, it may be omitted.

Preferably a relatively low partition wall 49 is attached to the lower section of the drum and is disposed between the screen 31 and the remainder of the drum, thus acting to prevent material from going through the drum 85 too rapidly.

It will thus be seen that with a structure of 90 this character, the mattress material is thoroughly picked, pulled apart, and loosened up and that during this process, the dust, dirt and other materials of any desired degree are withdrawn from the mattress and discharged 95 and that at any time desired the door or valve 42 may be opened so that the suction fan within the fan casing 39 will draw the material downward into the chute 38 and discharge the material out of the chute into the 100 mattress tick and that this discharge may be cut off at any time.

The structure is simple, may be cheaply made, but is found particularly effective.

There are certain features of operation 105 which it is thought best to reiterate and stress. One is that when the door 46 is opened and the valve 42 is closed, any cotton or hair or material that is being run through to be cleaned and worked over will be forced out 110 as it is cleaned through the door opening 45 instead of going through the passage into the tick as before explained.

The air relief door 44 relieves the suction 115 created by the dust removing fan so that the material will not move through the drum quite so rapidly and acts on the same principle as if the dust fan were slowed down which is not possible under these circumstances. This air port lets more air into the 120 lower drum and relieves the air pressure with the result that less dust and dirt is taken out through this dust fan than would be if it was not open. In going through the drum, the material is drawn in by the suction of the fan and with the centrifugal force is whipped around between the ends of the saws and the teeth projecting inward from the wooden braces of the drum so that it is thoroughly 125 picked and then it passes over the screen so 130

that it is thoroughly cleaned and then out through the spout 38.

I claim:—

1. A picker and renovator of the character described, comprising a drum formed in two sections, a frame supporting the lower section of the drum, the lower section of the drum having at one end a receiving hopper discharging into the interior of the drum and at its other end a bottom section having a stock discharge opening, the interior of the drum having inwardly projecting teeth, a shaft extending through the drum and provided with radially extending blades formed with radially extending teeth at their extremities, the lower section of the drum adjacent the receiving hopper having a dust outlet opening, a screen spaced from the wall of the drum but extending over said dust outlet, a dust box disposed below the lower section of the drum and communicating through said outlet with the interior of the drum, an exhaust fan having a housing communicating with the interior of the dust box and having driving engagement with the first-named shaft, a downwardly extending trunk communicating through said stock discharge opening with the interior of the drum and discharging into a horizontally extending chute, a fan disposed below the chute and having a housing communicating through the bottom of said chute, the fan having driving connection with the first named shaft, and manually operable means for cutting off communication between the drum and said chute.

2. A picker of the character described, comprising a drum having a stock inlet opening at one end and a stock outlet opening adjacent the other end, a dust outlet opening adjacent the stock inlet opening, a dust box connected to said dust outlet opening, a fan housing connected to the dust box and having an exhaust fan therein, a shaft extending through the drum and having beaters mounted thereon, the drum having a relief opening provided with a door.

3. A picker and renovator of the character described comprising a fixed drum having inwardly projecting teeth, a hopper opening through one end wall of the drum into the interior of the drum, the other end wall of the drum having a stock outlet, a shaft extending through the drum and carrying pickers thereon, a dust box communicating with the drum adjacent the hopper thereof, an exhaust fan driven from the shaft and having a housing communicating with the interior of the dust box, a discharge chute extending below the bottom of the drum and communicating with the interior thereof through said stock outlet, and a rotatable fan having a housing communicating with the interior of the chute.

In testimony whereof I hereunto affix my signature.
